ADOLF STEFFEN, OF PITTSBURGH, PENNSYLVANIA, ASSIGNOR TO ADAMS BROS. MFG. CO., INC., OF PITTSBURGH, PENNSYLVANIA, A CORPORATION OF PENNSYLVANIA

DESIGN FOR A GAS RADIANT HEATER

Application filed May 1, 1929. Serial No. 31,070. Term of patent 7 years.

To all whom it may concern:

Be it known that I, ADOLF STEFFEN, a citizen of the United States, and resident of Pittsburgh, in the county of Allegheny and State of Pennsylvania, whose post-office address is Number 1500 Fayette Street in the said city, have invented a new, original, and ornamental Design for Gas Radiant Heaters, of which the following is a specification, reference being had to the accompanying drawings, forming part thereof.

Fig. 1 is a front elevational view of a gas radiant heater, showing my new design, it being understood that the grille work is repeated throughout. Fig. 2 is a side elevational view thereof.

I claim: —

The ornamental design for a gas radiant heater, as shown and described.

ADOLF STEFFEN.
